UNITED STATES PATENT OFFICE

CONRAD C. C. BURKHARDT, OF PHILADELPHIA, PENNSYLVANIA

TENDER FRAME

Application filed November 29, 1930. Serial No. 499,100.

My invention relates to certain improvements in tender frames in which the frame is made in a single casting.

One object of my invention is to so design the frame that the water-carrying capacity of the tender will be considerably increased. This object I attain by depressing the center portion of the frame between the trucks.

A further object of the invention is to so construct the frame of the tender that the water capacity of the tender will be increased without increasing the over-all width of the tender.

A still further object of the invention is to so construct the tender that the height of the center of gravity of the combined mass of water, tank, and underframe will be lowered.

A still further object of the invention is to increase the depth of the central longitudinal sills, adding strength to the sills, and to provide integral cross transoms which materially increase the strength of the structure and provide baffles for the water within the tender.

In the accompanying drawings:

Fig. 1 is a diagrammatic side view of a tender, made in accordance with my invention;

Fig. 2 is a diagrammatic plan view;

Fig. 3 is a plan view of the frame of the tender;

Fig. 4 is a longitudinal sectional view on the line 4—4, Fig. 3;

Fig. 5 is a sectional view on the line 5—5, Fig. 4; and

Fig. 6 is a sectional view on the line 6—6, Fig. 4.

Referring to Figs. 1 and 2, 1 is the frame of the tender, which is made in a single casting. 2 is the body of the tender, which is mounted on the frame. This body can be of the ordinary construction. 3 is the water section of the tender and 4 is the fuel section, having inclined sides 5—5, and an inclined back 6. The fuel section may be provided with a flat bottom or may be constructed to receive a conveyor of an automatic stoker without departing from the essential features of the invention.

The frame 1, as stated above, is made as a single casting, and consists of end members 7, having transverse end sills 8, and suitable draft rigging pockets 9 at the outer end. The draft rigging pockets may be modified to accommodate different forms of draft rigging without departing from the essential features of the invention. The casting of each end member 7 of the frame is machined at 11 to receive the center plates 12 for the trucks 13. In some instances the center plate may be cast integral with the frame. The trucks shown in the drawing are 6-wheel trucks, but it will be understood that these trucks may be 4-wheel or 8-wheel trucks, and may be of any suitable design without departing from the essential features of the invention.

The center portion 14 of the frame is depressed between the trucks, materially increasing the water space of the tender, and shaping the frame in this manner decreases the height of the center of gravity of the tender. The side sills 15 are much deeper at the center than at the ends, as shown in Fig. 1, and form a girder-like structure. In the present instance these side sills have upwardly projecting flanges 15a, to which the side plates 33 of the tender are secured. The two central longitudinal sills 17 are of considerable depth. They extend below the side sills and above the side sills at the center of the truck, as shown in Figs. 4 and 6, forming truss members between the two trucks. These longitudinal sills 17 have openings 18 at intervals, which allow for the circulation of water and considerably lighten the structure without materially decreasing the strength, and the longitudinal central sills 17—17 are joined together at intervals by cross transoms 19, and are connected to the side sills by cross transoms 20. The upper portions of the cross transoms 20 are inclined and extend from the upper edge of the side sills to the top of the central sills. The cross transoms 19 have openings 21, and the transoms 20 have openings 22 therein, respectively, which also tend to lighten the structure. The transoms are in the form of deep flanges which form baffle

plates which tend to prevent the water in the depressed portion from surging fore and aft while the tender is in motion. The cross transoms 23 are substantially solid and extend the full width of the frame, and also act to prevent the water surging fore and aft. The upper surface of the cross transoms are flanged as at 24, forming with the flanges 25 of the central sills and the flanges 26 of the side sills, an open top section. The upper surfaces of the cross transoms are provided with pads 27, which can be finished for applying other baffle plates extending upwardly into the tender proper.

15 At the forward end of the tender are two upright ribs 28, which are flanged as at 29 in the present instance, and these ribs may form a portion of a stoker trough when the same is used. It will be noticed that the 20 lower portion of the frame is solid throughout the entire frame. This forms the bottom of the tank and increases the capacity of the tank. In the present instance there are cross transoms 30 at each end section, 25 which form a compartment above the center plates 12. The space 31 beyond these compartments and the sills is open to the water chamber of the tender. 32 are outlets for the pipes leading to the locomotive feed water apparatus, and also providing for the 30 draining of the tank. Any suitable means for drawing the water from the depressed water space may be applied, such as a siphon, pump or injector. These parts form 35 no part of the present invention.

I claim:

1. An integral frame for a locomotive tender, having a depressed section at the center thereof; longitudinal side sills; and 40 two central sills extending the full length of the tender, the central sills extending the full depth of the depressed section of the frame and forming truss members for the frame.
2. An integral frame for a locomotive tender, having a depressed section at the center thereof; longitudinal side sills; two central sills extending the full length of the tender, the central sills extending the full 50 depth of the depressed section of the frame and forming truss members for the frame; and cross transoms in the depressed space, tying the central sills together and to the side sills.
3. An integral frame for a locomotive tender, having shallow end sections; a depressed central section forming an additional water space for the water section of the tender; longitudinal side sills and longitudinal central sills, the central sills being 60 higher than the side sills about the depressed portion, and forming truss members for the frame.
4. An integral frame for a locomotive tender, having shallow end sections; a de-

pressed central section forming an additional water space for the water section of the tender; longitudinal side sills and longitudinal central sills, the central sills being higher than the side sills about the depressed portion, and forming truss members for the frame; and cross transoms at the depressed portion connecting the side sills with the central sills, the upper portions of the side cross transoms being inclined and connecting the upper ends of the side sills with the upper ends of the central sills, said transoms forming baffle plates.

5. An integral frame for a tender of a locomotive, having shallow end sections and a depressed central section forming an additional space for the water section of the tender; and having longitudinal side sills and longitudinal central sills; and transverse cross transoms, said central sills and transoms having openings therein to allow for the free circulation of water in the depressed portion of the frame.

6. An integral frame for a tender of a locomotive, having shallow end sections and a depressed central section forming an additional space for the water section of the tender; and having longitudinal side sills and longitudinal central sills; and transverse cross transoms, said central sills and transoms having openings therein to allow for the free circulation of water in the depressed portion of the frame; and two transoms at each end of the depressed water space, forming baffle plates extending the 100 full width of the frame.

7. An integral frame for a tender of a locomotive, having shallow end sections and a depressed central section; and having side sills and longitudinal central sills spaced 105 apart; and cross transoms forming lateral braces for the structure and also acting as baffles for the water, the upper portions of the cross transoms having pads thereon, to which additional baffles may be secured.

8. An integral frame for a locomotive tender, said frame being shallow at each end and having a depressed central section, the bottom of the frame being solid throughout and forming an additional water space for the water section of the tender, said frame having longitudinal side sills and spaced longitudinal central sills, and also having cross transoms at intervals.

9. An integral frame for the tender of a locomotive, having shallow end sections and a depressed central section forming additional water space for the water section of the tender; longitudinal side sills and longitudinal central sills, the side sills having 125 upwardly projecting flanges to which the side plates of the tender can be secured.

10. An integral frame for the tender of a locomotive, having shallow end sections and a depressed central section forming ad-

ditional water space for the water section of the tender; longitudinal side sills and longitudinal central sills, one end of the frame having two upright ribs spaced apart, 5 said ribs having flanges at their upper ends and forming a portion of a stoker trough.

11. A frame for a locomotive tender, made as an integral casting and having end members and a depressed central portion 10 forming a lower truss member, and an upper member forming an upper truss member at the longitudinal center of the frame, these two members stiffening the frame between the two center plates for the trucks.
